CLAIM

I claim the ornamental design for a pillow, as shown and described.

DESCRIPTION

FIG. 1 is a perspective view of a pillow showing my new design.

FIG. 2 is a top plan view of the pillow, the bottom plan view being a mirror image.

FIG. 3 is a back elevation view of the pillow.

FIG. 4 is a front elevation view of the pillow.

FIG. 5 is a right side view of the pillow; and,

FIG. 6 is a left side view of the pillow.

1 Claim, 3 Drawing Sheets
